THERMOHYDROMETER

Leo Edelmann, Chicago, Ill.

Application July 3, 1943, Serial No. 493,451

7 Claims. (Cl. 73—34)

1

My invention relates to improvements in thermohydrometers, and particularly to a syringe type of hydrometer such as ordinarily used in testing battery solutions and the like.

An object of my invention is to provide an instrument of this character that will be of small compact form and size, and which will give a maximum of protection to the specific gravity and temperature indicating means.

Another object is to so construct the parts that the liquid and float containing and housing jar or barrel can be molded or otherwise made up of a plastic material, thus expediting manufacture and insuring uniform accuracy, while at the same time providing a jar or barrel that will not be readily broken or damaged when being handled or used, or in shipping.

Still another purpose is to provide a single and unitary barrel or jar member that will house and protect the indicating scale and the indicating portion of a thermometer and will present these portions in position to be readily viewed by the operator or user, in proximity to a specific gravity float element.

With the above and other objects in view, some of which will be apparent to those skilled in the art and others of which are inherent in the construction and use of this hydrometer, my invention includes certain novel features of construction and combinations of parts which will be hereinafter set forth in connection with the drawing and then pointed out in the claims.

In the drawing:

Figure 1 is a view in elevation illustrating an embodiment of my invention.

Fig. 2 is a vertical sectional view taken substantially at right angles through the structure as illustrated in Figure 1.

Fig. 3 is a sectional view similar to Fig. 2, showing only the barrel or housing.

Fig. 4 is a top plan view of the barrel or jar.

Fig. 5 is a transverse sectional view substantially on line 4—4 of Fig. 2.

Fig. 6 is a bottom plan view of the jar or barrel as this appears before assembly.

Fig. 7 is a view in perspective showing the plug employed to close the lower end of the jar or barrel.

The jar or barrel 1 is made of the usual or ordinary elongated substantially cylindrical shape, and is provided at its upper end with an annular bead 2 received in a correspondingly shaped recess of the mounting sleeve of a suction bulb 3. At its lower end, this barrel or housing 1 is provided with an annular bead 4 fitted within a corre-

2

spondingly shaped recess of the mounting sleeve of a nozzle member 5. This nozzle member has a liquid receiving chamber 6 in the upper part thereof, with the passage of the liquid intake and discharge nozzle tip 7 communicating therewith.

The barrel or housing 1 has a liquid receiving chamber 8 therein which is preferably substantially circular in cross section, and while extending longitudinally of the barrel is eccentrically disposed toward one side, as perhaps best shown in Figs. 4 and 5 and 6. The liquid receiving chamber 8 is of relatively less diameter than the outer diameter of the barrel or housing 1, and the eccentric disposition toward one side of the barrel or housing leaves the opposite wall relatively thicker. A substantially crescent shaped thermometer housing opening 9 is molded or otherwise formed in this thickened portion of the barrel or housing, the parts being so constructed and formed that the liquid container opening 8 and the thermometer housing opening 9 are entirely separate.

This barrel or housing 1 is preferably molded of a transparent plastic material that will be resistant to battery acid, to sulfuric solutions, and in fact to any and all solutions that may be tested with the instrument, and the clear transparent walls thereof will permit a ready view through the barrel or housing in both the portions 8 and 9.

This barrel or housing 1 has the lower end 30 thereof molded or cored out in an enlarged substantially circular opening, as at 10, and the wall 11 between the openings 8 and 9 is eliminated within the enlarged opening 10. A cork or plug 12, perhaps best shown in Fig. 7, has the main body portion 13 thereof of a size and shape to accomplish a liquid-tight fit within the opening 10, and is provided with an extension plug portion 14 eccentrically disposed on its upper side in position to fit within the lower end of the liquid receiving compartment 8, thereby making a liquid-tight closure between the extension plug or cork 14 and the wall of the opening 8. This cork or plug 12 has a liquid passage 15 through the body portion 13 and the extension 14 thereof 40 establishing communication from the liquid chamber 6 of the nozzle member 5 to the liquid and float receiving chamber 8, and a thermometer receiving opening 16 is provided through the body portion 13 of the cork or plug to be substantially 45 centered with the crescent shaped thermometer housing opening 9.

In molding or otherwise making the barrel or housing 1, it will be found perhaps necessary or advisable to leave an opening through the upper end in line with the thermometer housing opening

8, and this opening will be closed by a suitable plug or other filler 17. A cork or stopper 18 is fitted in the upper end of the opening 8 to guard against a specific gravity float element 19 in this liquid and float chamber 8 rising into the bulb 3, and this cork or stopper is provided with a suitable opening to establish free communication between the interior of the suction bulb 3 and the upper end of the container opening 8.

A thermometer 20 is mounted through the opening 16 with its indicating portion 21 extending upwardly substantially centrally and housed within the substantially crescent shaped housing opening 9, and with its lower bulb or temperature influenced end 22 extending into the liquid chamber 6 of the nozzle member 5 where it will be exposed to a test quantity of liquid as drawn through the nozzle 7 and into the liquid and float chamber opening 8.

A scale sheet member 23 is inserted in the thermometer housing opening 9 adjacent to the indicating portion 21 of the thermometer 20, and on one side this scale member can be marked in degrees of temperature, as at 24, whereas on the opposite side of the indicating portion 21 of the thermometer the scale can be marked with figures, as at 25, indicating corrections at different liquid temperatures of the test quantity of liquid, as indicated by the thermometer 20.

As has been stated, the barrel or housing 1 can be molded or otherwise made up of any suitable plastic material, and the parts can be readily and conveniently assembled into the complete hydrometer. Due to the peculiar shape of the jar or barrel, and due to the fact that the wall 11 extends somewhat transversely therein, the barrel or jar will be strong and substantially resistant to crushing or breakage, even though the walls be made relatively thin; and when the thermometer is assembled for use this barrel or housing structure will afford a maximum of protection for the float element 19 and the thermometer 20. The indicating portion 21 of the thermometer will be housed and protected within the housing opening 9, and the bulb portion 22 of the thermometer will be within the liquid chamber 6 and will be protected by the nozzle portion 5.

As disclosed in Fig. 5, the scale member 23 can be a single piece of sheet material bent and shaped to fit within the opening 9 substantially behind and around the indicating portion 21 of the thermometer, with the side portions of this sheet disposed on opposite sides of the indicating portion 21 to thus present the indications at 24 and 25 closely adjacent to the indicating column of this indicating portion 21.

The gauge stem 26 of the float element 19 can be provided with a scale showing the indications thereof to represent the specific gravity of battery acid or any other solution to be tested, and in the present instance this specific gravity indicating float element is marked off in divisions representing substantially two points difference of specific gravity, with the scale calibrated at 80 degrees F., or in other words at 80-80. With the calibration point or temperature on the scale 24 indicated as zero on the scale 25, the divisions of the scale 25 are marked above and below zero at two degree intervals, and specific gravity corrections for temperature can be readily made by noting the position of the indicating column of the thermometer 20 and then adding the corresponding figure of the scale 25 or subtracting the same from the specific gravity reading as indi-

cated on the stem 26 of the float 19 at the liquid level within the liquid chamber opening 8.

In the present instance I have shown an adaptation capable of being used to test liquid solutions within a specific gravity range from 1.070 to 1.430, and a temperature range of from 30 degrees below zero F. to 140 degrees above zero F., with accompanying and appropriate corrections indicated both above and below the calibration temperature at 80 degrees F.

While this invention has been described with respect to certain particular embodiments which give satisfactory results, it will be understood that various changes and modifications can be made without departing from the spirit and scope of my invention, and it is intended therefore in the appended claims to cover all such changes and modifications.

I claim:

1. A combined liquid barrel and thermometer housing jar for a thermohydrometer comprising an elongated integral molded plastic member of substantially cylindrical outer form, said jar having a liquid receiving barrel opening of substantially less diameter than the outer diameter of said jar extending longitudinally therethrough and offset eccentrically toward one side of said jar, and being provided with a substantially crescent shaped thermometer housing opening extending longitudinally of the jar in the side away from the barrel opening, a closure for one end of said thermometer housing opening, said jar being provided at one end with an enlarged opening substantially circular in cross section and having the wall between the liquid barrel and thermometer housing openings stopped at the inner terminus of said enlarged opening, and a closure member fitted in said enlarged opening and having a protuberance extending into and closing the adjacent end of the liquid receiving barrel, said closure member having a liquid passage therethrough leading to the liquid receiving barrel opening and being provided with an opening aligning with the thermometer housing opening.
2. A combined liquid barrel and thermometer housing jar for a thermohydrometer comprising an elongated integral molded transparent plastic member of substantially cylindrical outer form, said jar having a liquid receiving barrel opening of substantially less diameter than the outer diameter of said jar extending longitudinally therethrough and offset eccentrically toward one side of said jar, and being provided with a thermometer housing opening extending longitudinally of the jar in the thickened part thereof, and a closure for one end of said thermometer housing opening, said jar being provided at one end with an enlarged opening substantially circular in cross section and having the wall between the liquid jar and thermometer housing openings stopped at the inner terminus of said enlarged opening.
3. A thermohydrometer jar comprising an elongated generally cylindrical integral transparent member having a liquid receiving barrel opening of substantially circular cross section extending longitudinally therethrough of relatively less diameter than the diameter of said cylindrical member and offset toward one side thereof, said jar member being provided with a longitudinally extending thermometer housing opening of substantially crescent shape offset toward the opposite side of the jar member and lying substantially around the adjacent side of the barrel opening, said jar member being provided at one end with an enlarged opening substantially circular in cross

section and having the wall between the liquid barrel and the thermometer housing openings stopped at the inner terminus of said enlarged opening.

4. A thermohydrometer comprising a combined liquid barrel and thermometer housing jar member of integrally molded plastic of substantially elongated cylindrical outer form, said jar having a liquid receiving barrel opening of substantially less diameter than the outer diameter of said jar extending longitudinally therethrough and offset eccentrically toward one side of the jar, and being provided with a substantially crescent shaped thermometer housing opening extending longitudinally of the jar in the side away from the barrel opening, a closure at one end of the jar for said thermometer housing opening, said jar being provided at the other end with an enlarged opening substantially circular in cross section and having the wall between the liquid barrel and thermometer housing openings stopped at the inner terminus of said enlarged opening, a closure member fitted in said enlarged opening and having a protuberance extending into and closing the adjacent end of the liquid receiving barrel, said closure member having a liquid passage therethrough leading to the liquid receiving barrel opening and being provided with an opening aligned with the thermometer housing opening, a thermometer fitted through the last mentioned opening with an indicating stem within the thermometer housing opening and a temperature influenced portion extending outwardly from said closure member, a liquid nozzle fitted at the end of the jar and enclosing the temperature influenced portion of the thermometer, and suction means at the opposite end of the jar communicating with the liquid receiving barrel opening.

5. A thermohydrometer jar comprising an elongated generally cylindrical integral transparent molded plastic member having a liquid receiving barrel opening of substantially circular cross section extending longitudinally therethrough and of relatively less diameter than the diameter of the member and offset toward one side thereof, and having a thermometer housing opening of substantially crescent shaped cross section lying around the inner side of the circular

opening with the jar member thus having a dividing wall extending across between the openings and each of the openings having a single outer transparent viewing wall, said jar having the thermometer housing opening closed at one end and having an enlarged opening at the other end with the dividing wall stopped at the inner end of the enlarged opening.

6. A thermohydrometer jar comprising an elongated integral transparent moulded plastic member having a liquid receiving barrel opening of substantially circular cross section extending longitudinally therethrough and offset toward one side thereof, and having a thermometer housing opening of substantially crescent shaped cross section lying around the inner side of the circular opening with the jar member thus having a dividing wall extending across between the openings and each of the openings having a single outer transparent viewing wall, said jar having the thermometer housing opening closed at one end and having an enlarged opening at the other end.

7. A thermohydrometer jar comprising an elongated integral transparent molded plastic member having a liquid receiving barrel opening extending longitudinally therethrough and offset toward one side thereof, and having a thermometer housing opening extending longitudinally thereof at the inner side of the liquid receiving barrel opening with the jar member thus having a dividing wall extending across between the openings and each of the openings having a single outer transparent viewing wall, said jar having the thermometer housing opening closed at one end and having an enlarged opening at the other end.
